DRILL POINTING MACHINE

Alexander Stephanoff, Detroit, Mich.

Application November 16, 1956, Serial No. 622,683

14 Claims. (Cl. 51—84)

This invention relates generally to grinding or abrading machines, and, more particularly to a machine of this type which is especially adapted to finish grind the points on twist drills, and other similar tools or cutters.

It is the primary object of this invention to provide an automatic twist drill pointing machine which is adapted to accurately finish grind the points on twist drills with the proper angle and clearance and at a high rate of production. The machine of the present invention generally comprises a rotary fixture adapted to carry a plurality of twist drills and to alternately move the drills into operative grinding engagement with a pair of laterally spaced apart grinding wheels as the fixture is simultaneously rotated and reciprocated, so as to finish grind the pointed end of each of the drills on opposite sides thereof and thus produce an accurately ground and centered point on each of the drills. The drills are fed by a hopper to the rotary fixture and are automatically located, indexed to the proper position for grinding, clamped, ground, and ejected at a highly efficient rate of production.

It is another object of this invention to provide an automatic twist drill grinding machine which is economical of manufacture, simple of structure, durable and compact, and highly efficient in operation.

Other objects, features and advantages of this invention will be apparent from the following detailed description and appended claims, reference being had to the accompanying drawings forming a part of the specification wherein like reference numerals designate corresponding parts of the several views.

In the drawings:

Fig. 1 is a top plan view, with parts removed and parts broken away, of a twist drill grinding machine made in accordance with the principles of the invention;

Fig. 2 is a side elevational view of the structure illustrated in Fig. 1, taken substantially in the direction of the arrow marked "2," with parts broken away and parts in section;

Fig. 3 is an end elevational view of the structure illustrated in Fig. 1, taken substantially in the direction of the arrow marked "3";

Fig. 4 is an enlarged end view of a drill clamping fixture employed in the invention, and showing an air cylinder adapted to position a drill in the fixture;

Fig. 5 is a top plan view of the drill clamping fixture illustrated in Fig. 4, taken in the direction of the arrow marked "5";

Fig. 6 is a plan view of an adjustable eccentric stud used in the drill clamping fixture of Fig. 5;

Fig. 7 is an end view of the eccentric stud illustrated in Fig. 6, taken along the line 7—7 thereof;

Fig. 8 is a side elevational view of the clamping fixture shown in Fig. 4, taken in the direction of the arrow marked "8," and showing the cam locking means for the fixture;

Fig. 9 is an enlarged top plan view, partly broken away

2

and partly in section, of the drill locator means employed in the invention;

Fig. 10 is an enlarged side elevational view of the drill contacting member employed on the drill locator shown in Fig. 9;

Fig. 11 is an end elevational view of a carrier member employed on the drill locator shown in Fig. 9, taken along the line 11—11 thereof;

Fig. 12 is a vertical sectional view of the structure illustrated in Fig. 11, taken along the line 12—12 thereof;

Fig. 13 is an end elevational view of the structure illustrated in Fig. 10, taken in the direction of the arrow marked "13";

Fig. 14 is an elevational view of the structure illustrated in Fig. 9, taken in the direction of the arrow marked "14";

Fig. 15 is a partial elevational view of the structure illustrated in Fig. 14, taken along the line 15—15 thereof;

Fig. 16 is a plan view of the cam and cam roller adapted for actuating the drill carrying rotary fixture forwardly and backwardly;

Fig. 17 is an enlarged partial elevational view of the drill ejector structure illustrated in Fig. 1, taken along the line 17—17 thereof;

Fig. 18 is a partial plan view of the structure illustrated in Fig. 17, taken along the line 18—18 thereof;

Fig. 19 is an enlarged partial elevational view of the structure illustrated in Fig. 1, taken along the line 19—19 thereof, and showing the rail for actuating the drill fixtures clamping means;

Fig. 20 is an end view of a drill showing the manner in which the drill locator engages a drill;

Fig. 21 is a partial elevational view of a drill adapted to be finished ground by the apparatus of the present invention;

Fig. 22 is an end elevational view of the right grinding wheel, taken along the line 22—22 of Fig. 1, showing the position of the drills in grinding one side of a drill point;

Fig. 23 is an end elevational view of the left grinding wheel, taken along the line 23—23 of Fig. 1, showing the position of the drills in grinding the other side of a drill point;

Fig. 24 is a plan view of a modified grinding wheel adapted for use in the invention;

Fig. 25 is an end view of the structure illustrated in Fig. 24, taken along the line 25—25 thereof;

Fig. 26 is an elevational side view of one of the grinding wheels shown in Fig. 1, taken in the direction of the arrow marked "26," and showing the path followed by the drill point during the grinding of the first side of the drill point; and

Fig. 27 is an elevational side view of the other grinding wheel shown in Fig. 1, taken in the direction of the arrow marked "27," and showing the path followed by the drill point during the grinding of the second side of the drill point.

Referring now to the drawings, and, in particular to Figs. 1, 2 and 3, an illustrative embodiment of the invention is shown which includes a rotary fixture base 10 that is provided on its upper side with a horizontally disposed longitudinally extended dovetailed guide 11. A horizontal carriage or slide 12 is slidably mounted on the guide 11 with its longitudinal axis normal or at a right angle to the longitudinal axis of the guide 11. The slide 12 is adapted to be moved on the guide 11 by means of the elongated screw rod 13, the inner end 70 of which is threadably mounted in the slide 12 in the usual manner and the outer end of which is rotatably

mounted in the arm 14 which is fixedly mounted, in any suitable manner, as by welding, on the outer end of the base 10.

A supporting bracket 15 is fixedly mounted on the outer end of the base 10, by any suitable means, as by the bolts 16. Fixedly mounted on the bracket 15 is a conventional gear reduction means 17 which is connected to the outer end of the screw rod 13 by means of the coupling 18. Fixedly mounted on the bracket 15 is a constant speed electric motor 19 which is connected to the gear reduction means 17 by means of the coupling 20. The motor 19 and gear reduction means 17 are adapted to continuously rotate the screw rod 13 so that the slide 12 will be advanced or retracted along the guide 11 approximately thirty thousandths of an inch per revolution of the screw rod. This will permit the drills to always move longitudinally of the grinding wheels over a clean part thereof and provide even wear on the grinding wheels. It will be understood that the movement of the slide 12 could also be regulated in accordance with the movement of a predetermined number of drills engaging the grinding wheels, and a suitable gear reduction means and constant speed motor could be selected accordingly.

The motor 19 may be reversed at the end of the advance or retraction travel of the slide 12 by any suitable means, as by the following means. The motor 19 is connected by means of the conductor lines 20a to a usual electrically operated reversing switch 21 which is connected to a suitable source of electrical power indicated by the numeral 22. A first micro-switch 23 is fixedly mounted on the base 10 adjacent the rear end thereof and is connected to the reversing switch 21 by the conductor lines 24. A second micro-switch 25 is fixedly mounted on the base 10 adjacent the forward end thereof and is connected to the reversing switch 21 by the conductor lines 26. The switches 23 and 25 would be set apart a distance equal to the desired length of travel of the drills lengthwise to the grinding wheels. The switches 23 and 25 are operated by means of the rigid downwardly extended arm 27 which is fixedly mounted on the adjacent end of the slide 12, as by means of the bolt 28. The contacting of the switches 23 and 25 by the arm 27 will operate these switches which in turn operate the motor reversing switch 21.

The slide 12 is provided on its upper side with a longitudinally disposed dovetailed guide 29 on which is slidably mounted a second slide or carriage 30 which carries the housing generally indicated by the numeral 31. The housing 31 is swivelly mounted on the second slide 30 by means of the swivel pin 32 (Fig. 1) and is adapted to be secured in an adjusted position by any suitable means, as by the bolt 33. As shown in Figs. 1 and 3, the bolt 33 passes through the arcuately shaped aperture 34 in the bracket 35 which is fixedly mounted on the housing 31, and this bolt then is threadably engageable in a suitable aperture in the upper side of the slide 30. The housing 31 may thus be adjusted relative to the slides 12 and 30 to provide for different positions for grinding drills having differently angled points. For example, the drill illustrated in Fig. 21 has an angled point of 59° and so the housing 31 would be set to provide an angle of 59° between the longitudinal axis of the guide 11 and the longitudinal axis of the housing 31. This angle is indicated in Fig. 1 by the letter "x."

The second or upper slide 30 is adapted to be moved on the first or lower slide 12 by the following described means. Fixedly mounted on the inner end of the slide 12 is a vertically extended arm 36 having a recess 37 on the inner side thereof in which is nested one end of a coil spring 38, and this is best seen in Figs. 1 and 2. The other end of the coil spring 38 is nested in a recess as 39 in the inner end of the slide 30. The coil spring 38 functions to normally bias or move the slide 30 on the guide 29 toward the outer end or right end of the slide 12, as viewed in Fig. 3. A drive motor 40 is fixedly

mounted on the upper side of the body portion 41 of the housing 31, as by the bolts 42, and has extended from one end thereof the horizontal drive shaft 43.

Fixedly mounted on the top side of the end cover portion 44 of the housing 31 is a gearing housing 45 through the front wall of which is rotatably mounted a stub shaft 46. As shown in Fig. 2, the shaft 46 is connected at its front end with the motor shaft 43 by means of the coupling 47. A bevel gear 48 is fixedly mounted on the rear end of the shaft 46 and this gear is meshably engageable with the bevel gear 49 which is fixedly mounted on the upper end of the vertically disposed driven shaft 50. Any suitable meshable pair of miter or worm gears could be used in place of the bevel gears 48 and 49. The vertical shaft 50 passes through the lower wall of the gear housing 45 and through the upper wall of the housing portion 44 and is rotatably mounted in these walls by any suitable means, as by the sleeve bearing 51. The gear housing 45 is open on the upper side thereof and this opening is adapted to be enclosed by means of the cover plate 52 which is secured in place by the bolts 53. The cover portion 44 of the housing 31 is fixedly mounted on the body portion 41 by means of the bolts 54.

Fixedly mounted on the shaft 50, immediately below the sleeve bearing 51, is a bevel gear 55. The lower end of the shaft 50 extends downwardly through the stationary arm 56 which is fixed on the inner side of the housing cover portion 44. The bevel gear 57 is fixedly mounted on the lower end of the shaft 50 below the arm 56 and it meshably engages with the idler gear 58 which is rotatably mounted on the hub or boss 59 on the housing cover portion 44. The idler gear 58 meshably engages the bevel gear 60 which is a gear similar to the gear 57 and which is fixedly mounted on the upper end of the vertically disposed shaft 61. The shaft 61 passes downwardly through the fixed arm 62 and the lower wall of the housing cover portion 44 and is suitably journaled therein. Fixedly mounted on the shaft 61 between the arm 62 and the lower wall of the housing portion 44 is the bevel gear 55a which is similar to the gear 55. Fixedly mounted on the lower end of the shaft 61 is a drive worm gear 63 which is meshably engaged with the driven worm gear 64 which is fixedly mounted on the shaft 65. As shown in Fig. 3, one end of the shaft 65 is rotatably mounted in the arm 66 which depends from the housing cover portion 44 and which is fixedly secured thereto by any suitable means, as by the bolt 67. The other end of the shaft 65 is fixed to one end of a splined sleeve member 68 and the other end of the splined sleeve member 68 slidably receives one end of a shaft 69, which end is splined.

As shown in Figs. 1 and 3, the outer end of the shaft 69 is suitably rotatably journaled in the bracket 70 and has fixedly mounted on its outer end the drive bevel gear 71 which meshes with and drives the driven bevel gear 72 which is fixedly mounted on the upper end of the shaft 73. The shaft 73 is rotatably mounted in the outwardly extended upper arm 74 of the bracket 75. The bracket 75 is fixedly mounted on the outer end of the slide 30 by any suitable means, as by the bolts 76. The bracket 70 is adjustably mounted on the bracket 75 by means of the arcuate slot 76 and the lock bolt 77, so as to permit swiveling of the bracket 70 on the bracket 75 when the housing 31 is adjusted.

The bracket 75 is provided with the lower outwardly extended arm 78 in which is suitably journaled the lower end of the shaft 73. As shown in Figs. 1 and 16, an elliptically shaped cam 79 is disposed between the arms 74 and 78 and is fixedly mounted on the shaft 73 by means of the lock key 80. The cam 79 is adapted to rollably engage the cam roller 81 which is rotatably mounted on the shaft 82 on the bracket 83. The bracket 83 is fixedly mounted on the slide 84 which is slidably mounted on the guide 29 of the slide 12. The slide

84 is adjustable by means of the screw rod 85, the inner end of which is threadably connected to the slide 84 in the usual manner and the outer end of which is rotatably mounted in the bracket 86 which is fixedly mounted on the outer end of the slide 12. The screw rod 85 is operable by means of the handwheel 87 which is fixed on the outer end of the rod 85. It will be seen that the coil spring 38 normally urges the slide 30 outwardly so as to maintain the cam 79 in continuous engagement with the cam roller 81, and, that when the cam 79 is turned by the shaft 73, the slide 30 will be moved inwardly toward the arm 36 a distance equal to the eccentric throw distance of the cam 79, as indicated by the numeral 88, and then moved outwardly toward the bracket 83 the same distance.

As shown in Figs. 1, 2 and 3, the numeral 89 generally indicates a rotatable spider arm type rotary fixture which includes the hub 90 which is adapted to rotate in the vertical plane. Fixedly secured to the hub 90, by any suitable means, is the journal 91 which is horizontally rotatably mounted in the longitudinal aperture 92 in the body portion 41 of the housing 31. The journal 91 is adapted to be rotatably carried in the tapered roller bearings 93 and is retained in place in the housing portion 41 by means of the annular retaining ring 94 which is threadably mounted on the rear end of the journal 91 and is secured in place by the lock bolts 95. Fixedly mounted on the rear end of the journal 91 is a beveled ring gear 96 which is affixed thereto by means of the screws 97 and the boss 98 on the rear end of the journal 91. The ring gear 96 meshes with and is driven by the two bevel gears 55 and 55a which are fixedly mounted on the drive shafts 50 and 61, respectively.

As shown in Figs. 1, 2 and 3, the rotary fixture 89 is provided with a plurality of fixedly mounted spider arms 99 which are evenly arranged around the circumference of the hub 90 and which extend vertically and outwardly laterally from the hub 90 in the direction opposite to the journal 91. Fixedly mounted on the outer end of each of the spider arms 99 is a drill holding and clamping fixture indicated generally by the numeral 100. As best seen in Fig. 1, 4, 5 and 8, the drill fixtures 100 each include a body 101 which is fixedly mounted on the outer end of a spider arm by any suitable means, as by welding. Each of the bodies 101 is provided with a transverse groove 102 adjacent the front end thereof in which is fixedly mounted a V-block 103, the ends of which extend beyond the sides of the body 101. The V-block 103 is adapted to support a drill which is to be ground, as 104, and is fixedly secured in the groove 102 by any suitable means, as by the bolts 105. The drill 104 is releasably clamped in the V-block 103 by means of the clamp 106 which is provided with the two drill engaging arms 107 on the front end thereof. The clamp 106 is provided on the rear end thereof with an enlarged portion 108 through which is formed a transverse aperture 109 in which is rotatably mounted the pivot pin 110.

As best seen in Figs. 5, 6 and 7, the pivot pin 110 is provided on each end thereof with an eccentrically mounted square, outwardly extended portion 111. The square portions 111 are adapted to be mounted between a pair of integrally formed upwardly extended portions or shoulders, as 112 and 113, on each side of the body 101 adjacent the rear end thereof. Extending outwardly from each of the square portions 111 is a centrally disposed round shaft 114 around which is mounted the upper end of a clip spring as 115. The lower ends of the clip springs 115 are mounted around the integral pins 116 on each side of the body 101. The clip springs 115 also each abut one of the shoulders 113 which extend down the sides of the body 101. The clamp 106 is provided on the rear end thereof with a downwardly extended tail portion 117 through which is threadably mounted a screw 118, the end of which abuts the rear end of

the body 101. The clamp 106 is adapted to pivot on the pin 110 and the screw 118 functions to limit the upward movement of the clamp 106. The eccentric mounting of the square portions 111 permits the pin 110 to be rotatably adjusted to various positions to permit the clamp 106 to be raised to a higher position when drills of larger diameter are to be held in the drill fixture for grinding.

The drill clamping fixtures 100 each include a clamping stud 119 which passes through the aperture 120 in the clamp plate 106 and through the aperture 121 in the fixture body 101. The stud 119 is provided on the upper end thereof with an enlarged head portion 122 which is adapted to abut the top face of the clamp plate 106. Mounted around the stud 119 and between the clamp plate 106 and the fixture body 101 is a coil spring 123 which tends to bias the clamp plate 106 upwardly around the pin 110 to permit the loading and unloading of a drill 104 from the drill fixture 100. The stud 119 is provided with an annular washer 124 on its lower end at a point below the fixture body 101. A second coil spring 125 is mounted around the stud 119 with the lower end thereof abutting the washer 124 and with the upper end thereof seated in the recess 126 in the lower face of the fixture body 101. Spring 125 is a stronger or heavier tension spring than spring 123, and, accordingly, the clamp plate 106 is normally urged downwardly into clamping engagement with the drill 104 in the V-block 103.

The clamping force exerted by the heavy tension spring 125 is strong enough to hold the drills in place in the V-blocks 103 during the indexing and positioning actions described hereinafter, however, a cam lock means, generally indicated by the numeral 127, is provided for locking the clamp stud 119 in place during the grinding action to provide additional holding force which is necessary when the drills are being ground.

As best seen in Figs. 1, 2, 4 and 8, the cam lock means 127 includes an arm 128, the lower end of which is bifurcated and pivotally connected by the pin 129 to the clamp stud 119 below the washer 124. The bifurcated lower end of the arm 128 is rounded off and extends outwardly as at 130 to form a cam nose which contacts the washer 124 when the arm 128 is pivoted to the locked position shown in dotted lines in Fig. 4. The unlocked position of arm 128 is shown in Fig. 4 in the solid lines.

The upper end of the arm 128 is pivotally connected by means of the pivot pin 131 to the outer end of a piston rod 132. The other end of the piston rod 132 is slidably mounted in the outer end of a suitable air cylinder 133 and is fixedly connected to the piston 134. The air cylinder 133 is pivotally mounted at the inner end thereof on the spider arm 99 by means of the integral arm 135 which is pivoted on the pin 136 on the spider arm 99.

Air under pressure is supplied to the opposite ends of the air cylinder 133 by means of the tubes or conduits 137 and 138 which are connected to the flow reversing valve 139. The valve 139 is operated by the push button 140 which is in turn actuated by the bar 141 in one direction and which is spring actuated in the other direction in the usual manner as more fully described hereinafter. The bar 141 is fixedly mounted on the arms 142 which are fixedly mounted on the vertical supporting member 143 by any suitable means, as by the bolts 144. The supporting member is provided at the lower end thereof with the integral flanges 145 which are fixedly mounted on the housing portion 41 by means of the bolts 146.

Air under pressure is supplied to the valve 139 through the conduit 147 which is connected to the air cap 148. The air cap 148 has an outlet for each of the conduits 147 for all of the spider arms 99 and these outlets are connected to a passage 149 through the hub 90 which passage communicates with the air chamber 150 inside of the journal 91. The air chamber 150 is supplied with air under pressure through the conduit 151, the inner

end of which is fixed in the flange 152 which is secured to the journal 91 by means of the bolts 153. The conduit 151 extends through the ring gear 96 and is rotatably mounted in the boss 59 and outer wall of the housing portion 44. The outer end of the conduit 151 is rotatably mounted in a swivel unit 154 and is connected to the stationary conduit 155 by means of the usual swivel connection means 156. The conduit 155 is adapted to be connected to a suitable air compressor.

As best seen in Figs. 1, 2 and 3, the vertical supporting member 143 is provided on its upper end thereof with an integral forwardly extended horizontal arm 157 which is disposed over the rotary fixture 89 on the vertical plane through the rotary axis of said fixture. A gravity feed drill hopper 158 is fixedly mounted on the horizontal arm 157 by means of the support members 159. The hopper 158 is disposed in vertical alignment over the path of travel of the drill holding fixtures 100 and is adapted to feed the drills 104 to be ground into the drill fixtures 100 as they pass underneath. The drill hopper 158 is provided on the lower end thereof with a narrowed neck portion 160 which is adapted to align the drills 104 for singular downward movement of the drills to the drill holding fixtures 100. The hopper neck portion 160 is provided at its lower end with an inwardly extended finger, as 161, on each side thereof, and these fingers function to support the lowermost drill 104 in the hopper 158 in a position whereby it may be knocked out by the front end of the arms 107 on the clamp plate 106 and into the V-block 103. The hopper neck portion 160 is open at the lower end thereof, from the point indicated by the numeral 162 downwardly to permit the lowermost drill 104 to be removed from the hopper 158.

As shown in Figs. 2 and 3, a vertically disposed support shaft 163 is fixedly mounted on the outer end of the support arm 157 by any suitable means, as by welding. A collar 164 is slidably mounted on the lower end of the shaft 163 and is adapted to be secured in a desired adjusted position by means of the bolt 165. The collar 164 carries an integral outwardly extending arm 166 which extends toward the rotary drill carrying fixture 89. The arm 166 is provided on its outer end with an integral support arm 167 having a downwardly tapered portion 168 disposed under and in alignment with the travel path of the drill fixtures 100 and just ahead of the drill hopper position.

As best seen in Fig. 3, the support arm portion 168 is adapted to adjustably carry the curved riser bar 169 on which the lower ends 170 of the clamp studs 119 are adapted to ride and be raised as they pass thereover. As the clamp studs 119 are lifted by the riser bar 169 the tension of the heavy clamping springs 125 is overcome and the lighter springs 123 function to pivot the clamp plate 106 upwardly to the position shown in Fig. 8, whereby the drill fixture 100 is in a condition for the unloading and loading of a drill 104. The riser bar 169 is adjustably mounted on the arm portion 168 by means of the adjusting screws 171, which are threadably mounted in the arm portion 168 with the upper ends thereof being rotatably secured in the lower side of the riser bar 169 by any suitable means.

As best seen in Figs. 1, 17 and 18, a drill ejector means, generally indicated by the numeral 172, is disposed along the path of travel of the drill fixtures 100. The ejector means comprises a cylinder 173 which is fixedly mounted by any suitable means on the arm 174. The lower end of the arm 174 is pivotally mounted, as by means of the pin 175, on the arm 176 which is pivotally mounted on the projection 177 on the housing portion 41 by means of the pin 178. Fixedly mounted on the forward end of the cylinder 173 is the stub arm 179 which is adapted to extend into the path of travel of the drill fixtures 100 and to be engaged by the outwardly extending V-blocks 103 of the drill fixtures, so as to carry the ejection cylinder 173 a short distance along with the drill

fixtures while the ejection action is taking place. Projecting outwardly from the cylinder 173 is an ejection rod 180 which is adapted to align with the V-block 103 of a drill fixture 100 and, eject a drill 104 therefrom as the cylinder 173 is carried along by a drill fixture 100. The hingedly mounted arms 174 and 176 permit said arms to swing and tilt during the time the cylinder 173 is carried along by a drill fixture 100. The ejection rod 180 is slidably mounted in the cylinder 173 in the usual manner and is fixedly connected to the piston 181. The piston 181 is adapted to be biased inwardly to a non-operative position by means of the spring 182 and to be biased outwardly to move the ejection rod 180 into an operative position by means of a conventional solenoid 183. An arm 184 is fixedly mounted on the top of the housing portion 41 and has fixedly mounted on its outer end the substantially horizontally disposed support bar 185 which is provided with a stop 186 at the front end thereof. The arm 174 is provided with a projection or finger 187 which abuts the stop 186 when the ejection means is not functioning. A spring 188 is connected at one end thereof to the pin 189 on the arm 174, and at the other end thereof to the pin 190 on the housing portion 41. When the ejector means is carried along by a drill fixture 100, the arms 174 and 176 pivot on the pin 178 and the finger 187 slides on the bearing surface 191 (Fig. 18) on the support bar 185 and contacts the micro-switch 192. The micro-switch 192 is interconnected with the solenoid 183 and a suitable source of electric power, as 193, by means of the conductor lines 194, 195 and 196. At this point, the ejection action takes place and the drill 104 in the V-block 103 of a drill fixture 100 carrying the ejection means 172 therealong will be ejected by the ejection rod 180 into a suitable discharge chute, as 197 (Fig. 18). Continued movement of the ejection means 172 causes the finger 187 on the arm 174 to ride up the tapered cam rise surface 198, thereby causing the arm 174 to tilt backwardly around the pin 175, whereby the stub arm 179 is disengaged from the V-block 103 of the drill fixture 100 which carried the ejection means 172 along with it during the ejection process. The spring 188 then functions to return the ejection means 172 back to its initial position with the finger 187 against the stop 186. The spring 182 has in the meantime returned the ejection rod 180 to the inoperative position.

As best seen in Figs. 1 and 4, an air cylinder 199 is provided for positioning the drills 104 lengthwise in the V-blocks 103 of the drill fixtures 100 after the drills 104 have been loaded therein from the drill hopper 158. The air cylinder 199 is fixedly mounted on the support arm 157 by means of the arm 200. A vertical positioning plate 201 is fixedly mounted on the outer end of piston rod 202 which is fixedly connected to the piston 203 in the cylinder 199 in the usual manner. The positioning plate 201 is adapted to be moved outwardly against the pointed end of a drill 104 and its travel is limited by the stationary upwardly extending stop 204 which is fixedly mounted on the arm 205 which is in turn fixedly connected to the air cylinder 199. The air cylinder 199 is provided with the usual air inlet lines 206 and 207 and they in turn are connected to a solenoid type conventional flow control valve 208 which is connected to a suitable source of pressurized air, by means of the line 209 and to the atmosphere by the line 210. The flow control valve 208 is adapted to be actuated by the micro-switch 211 which is positioned at the exit end of the riser bar 169, whereby said switch 211 is actuated by means of the clamp stud lower end 170 when it contacts the switch 211 after the loading of a drill 104 in a drill fixture 100. The micro-switch 211 is interconnected by the lines 212 to the valve 208 and to a suitable source of electrical energy as 213.

As shown in Figs. 1, 2 and 9 through 15, a drill locator means is provided which is generally indicated by the numeral 214. The drill locator means 214 includes the

cylindrical sleeve 215 which is mounted on the shaft 163 above the collar 164. The shaft 163 is threaded immediately above the collar 164 and threadably mounted thereon is the nut 216, at a point below the sleeve 215. The nut 216 is fixed in place by means of the set screw 217. The sleeve 215 may be secured in an adjusted position by means of the set screw 218. The sleeve 215 may be adjusted upwardly and downwardly on the shaft 163 by means of the nut 216 upon which it seats or rests. Fixedly mounted on the sleeve 215 is the track 219 which is circular in part and which is straight along the side 220, and parallel along this side 220 to the path of travel of the drill fixtures 100. The upper surface of the track 219 is flat except on the straight part 220 which is curved on its upper surface similarly and in accordance with the path of travel of the drill fixtures 100. A carrier having the three arms 221 is rotatably mounted on the shaft 163 and it rests on the upper end of the sleeve 215, and, each of the arms 221 thereof, is provided with a slot 222 in which is slidably carried a slide as 223. Each of the slides 223 is provided with a vertical aperture 224 (Figs. 14 and 15) in which is slidably mounted the pin 225. The lower end of the pin 225 extends down into an enlarged aperture 226 in a slide block 227 and is swivelly secured to the block 227, as by the pin 228. A spring 229 (Figs. 14 and 15) is mounted around the pin 225 and is interposed between the slide 223 and the block 227. The blocks 227 (Figs. 14 and 15) slide on the track 219 and the springs 229 normally bias the blocks 227 downwardly into a sliding engagement with the track 219.

Each of the blocks 227 is provided with a lip 230 (Figs. 14 and 15) which engages the outer vertical face of the track 219. The blocks 227 are normally held in position with each lip 230 abutting the outer face of the track 219 by means of springs as 231, the inner ends of which are fastened by means of the pins 232 to the arms 221 and the outer ends of which are fastened by means of the pins 233 to the slides 223. The carrier supporting the arms 221 is journaled on the reduced neck 234 of an adjusting nut 235 which is threadably mounted on the shaft 162 and which is adapted to be locked in place by means of the set screw 236.

The slide blocks 227 are provided with an axial bore 237 in the front wall thereof which communicates with the larger bore 238 which extends the rest of the way therethrough. Rotatably mounted in the bore 237 is a spindle or shaft 239, the rear end of which is rotatably supported by the bushing 240. The rear end of the spindle 239 is splined as at 241. The gear 242 is slidably mounted on the splined end 241 of the spindle 239 and is retained against endwise movement by means of the retaining bracket 243 which is fixed to the block 227, by means of the cap screw 244.

As shown in Fig. 11, the bracket 243 is provided with an arcuate clearance opening 245 through which the splined shaft end 241 extends. As shown in Fig. 11, a stop 246 is provided on the back face of the block 227 against which the stud 247 on the gear 242 is adapted to abut. The coil spring 248 is mounted around the spindle or shaft 239 in the bore 238 and normally maintains the shaft 239 in a position whereby the stud 247 abuts the stop 246. The front end of the spring 248 is fixedly mounted in the block 227, as at 249, and the rear end of the spring 248 is fixedly mounted in the spindle 239, as at 250.

As shown in Figs. 10, 12 and 13, the front end of the spindle 239 is provided with an axial recess 251 in which is mounted the shaft 252 of a drill contact member having the enlarged head 253. The shaft 252 is fixed in the recess 251 by means of the set screw 254. The back face 255 of the enlarged contact head 253 is adapted to abut the front end of the spindle 239. The enlarged head 253 is provided with a tapered recess 256 substantially similar to the shape of the end of the drill 104 which is to be pointed, but being formed at an angle slightly less than the angle of the point of the drill. A pair of inserts, as

257, are mounted in the tapered recess 256 in an offset position so as to contact the offset lips of a drill 104 as shown in Fig. 20. The inserts 257 are fixedly mounted in the enlarged head 253 by any suitable means and they protrude outwardly a slight amount, as about $\frac{1}{16}$ of an inch. The inserts 257 must protrude outwardly a distance sufficient enough to catch the lips of a drill 104 for turning it and locating it in the drill fixture 100. Fixedly mounted on the leading side of the block 227 is a horizontal outwardly extended arm 258 which is secured thereto by means of the screws 259. As shown in Fig. 11, the underside of the block 227 which contacts the track 219 is curved as at 260 similarly to the curved upper surface of the straight portion 220 of the track 219.

15 As shown in Figs. 2, 9, 11 and 12, the spindle 239 is provided with an integral pin-shaped cam follower 261 on the rear end thereof. The cam follower 261 is adapted to engage the tapered face of the wedge-shaped cam 262 which is fixedly mounted on the track support member, 20 by means of the bolts 263, in a position inwardly of the straight portion 220 of the track. A gear rack 264 is disposed on the track support member between the cam 262 and the straight portion 220 of the track and this rack is parallel to said straight track portion. The gear 242 is 25 adapted to engage the rack 264 when the block 227 is moved over the curved upper surface section of the track, by means of a drill fixture 100 engaging the arm 258 and moving the block 227 along the curved upper surface of the straight portion 220 of the track 219.

30 The size of the circular track 219 is proportionate to the size of the circular path traveled by the rotary fixture 89 and to the number of stations or drill fixtures 100 carried on the rotary fixture 89, so that starting with a block 227 at the point "y," shown in Fig. 9, the extended V-block 103 of a drill fixture 100 will engage the arm 258 of said block and will move the block along the curved upper surface of the straight portion 220 of the track 219. During such travel, the gear 242 engages the rack 264 and the cam follower 261 engages the cam 262. As the 35 block 227 travels along the upwardly curved surface of the track portion 220, the spindle 239 will be cammed outwardly and the enlarged drill locator head 253 will engage the end of the drill 104 in the drill fixture 100 which is moving the block 227. Simultaneously, the 40 spindle 239 will be rotated clockwise, as viewed in Fig. 9, by means of the gear 242 rolling on the rack 264 and the inserts 257 will engage the lips on the drill point. When the block 227 has been moved a distance sufficient to permit the cam follower 261 to move off of the cam 262, the 45 spindle 239 will be positioned with the inserts 257 in a vertical plane, as shown in Fig. 20, and the drill 104 will be properly positioned for grinding. The inserts 257 will always end up in a vertical position at this drop-off point since the spring 248 returns the spindle 239 back to the 50 same initial starting point between locating operations by biasing the spindle 239 counter-clockwise until the stud 247 on the gear 242 abuts the stop 246 in the block 227. The cam follower 261 engages the cam 262 before the gear 242 engages the rack 264 so that the drill locator 55 head 253 on the spindle 239 is allowed to engage the point of a drill 104 before the gear 242 starts to turn on the rack 264. It will be understood that the rack 264 is curved similarly to the upper curved surface of the straight portion 220 of the track 219.

60 As shown in Figs. 1, 2 and 3, there are provided two similar grinding wheels, indicated by the numerals 265 and 266, which are set parallel to the base 10 on which the rotary fixture housing 31 is mounted. These grinding wheels are disposed to rotate on an axis which is disposed at an angle equal to the desired angle to be ground on the drills 104. As shown in Fig. 21, the angle of the illustrative drill is 59° and, accordingly, the grinding wheels 265 and 266 would be set with their longitudinal 65 axis at an angle of 59° to the axis of rotation of the rotary

drill fixture 89, and this setting angle is indicated in Fig. 1 by the letter "x." As illustrated in Fig. 22, the right grinding wheel 265, as viewed in Fig. 1, is adapted to grind the one relief surface 267 on a drill point from the heel 268 to the lip 269 as the rotary fixture 89 is moved outwardly, that is, as the slide 30 moves outwardly on the slide 12 away from the grinding wheels or to the right as viewed in Fig. 1. The heel 268 and lip 269 portions of the drill point are illustrated in Fig. 20. The left grinding wheel 266, as viewed in Fig. 1, is adapted to grind the other relief surface 270 on a drill point from the lip 271 to the heel 272 as the rotary fixture 89 is moved inwardly, that is, as the slide 30 moves inwardly on the slide 12 toward the grinding wheels or to the left as viewed in Fig. 1.

Since the grinding wheels 265 and 266 and their supporting structure are similar, only the one will be described. As shown in Fig. 2, the grinding wheel 266 is mounted on the shaft 273 against the flange 274 on said shaft. The grinding wheel 266 may be locked on the shaft 273 by any suitable means, as by the lock key 275. The grinding wheel 266 is fixed against end-wise movement on the shaft 273 by means of the retaining plate 276 and the nut 277. The shaft 273 is rotatably mounted in the slide block 278 which is slidably mounted on the guide 279 on the base 280. Fixedly mounted on the base 280, by means of the bolts 281, is an upwardly extended plate 282 through which is rotatably mounted a screw rod 283. Fixedly mounted on the end of the screw rod 283 is a handwheel 284 for actuating the rod 283. The inner end of the screw rod 283 is threadably mounted in the slide block 278, in the usual manner. The outer end of the shaft 273 carries the pulley 285 which is driven by the belts 286 which pass around the pulley 287. The pulley 287 is fixedly mounted on the end of the shaft 288 of the motor 289 which is fixedly mounted on the top of the slide 278, as by means of the bolts 290.

In operation, with the grinding wheels 265 and 266 set at the desired angle relative to the rotary fixture 89, and with the wheels dressed to approximately the same diameter, by any suitable means, the drill hopper 158 would be loaded with drills 104 with the points thereof facing toward the locating mechanism 214. The drills 104, at this stage, would be already rough turned with the points roughly formed thereon, and with only the finish pointing grinding operation remaining to be performed. The motors 19, 40 and 289 for driving the rotary fixture 89 and the grinding wheels 265 and 266 would then be actuated and the rotary fixture 89 and the grinding wheels 265 and 266 would then be actuated and the rotary fixture 89 would be rotated in a clockwise direction, as viewed in Fig. 3. Assuming a start with an empty drill fixture, as the drill clamping fixture 100 leaves the grinding wheel 266, the air control button 140 will engage the rail 141 and be operated to let air enter conduit 138 to move the piston 134 from the position shown in Fig. 1 to the position shown in Fig. 2 whereby piston rod 132 will pivot arm 128 to the position shown in Fig. 1 and the clamp stud 119 will be unlocked. The pivotal mounting of the air cylinder permits the necessary swiveling of the air cylinder during operation thereof. The lower end 170 of the clamp stud 119 then engages the riser rail 169 and stud 119 is pushed upwardly to overcome the tension of spring 125 whereby the clamp plate 106 will be pivoted upwardly around the pin 110 and will be in a position to receive a drill 104 from the hopper. Continued movement of the drill fixture 100 will bring the front edge of the front portions 107 of the clamp plate 106 into engagement with the lowermost drill 104 in the hopper 158 and the portions 107 will knock said drill from the lips 161 of the hopper into the V-block 103 of said fixture. Continued movement of the drill fixture 100 will cause the clamping stud 19 to ride down the downwardly tapered exit end 169a (Fig. 3) of the riser rail 169. The heavy

spring 125 in the drill fixture will then move the clamp plate 106 into a clamping engagement with the drill 104. The clamping stud 119 then rides off of the tapered rail end 169a and engages the micro-switch 211 which actuates the air cylinder 203. The air cylinder 203 then actuates the positioning plate 201 outwardly into engagement with the point of the drill 104 so as to position said drill to the proper length wise position in the V-block 103. Continued movement of the drill fixture 100 causes the extended V-block 103 to contact the arm 258 on one of the blocks 227 which is disposed at the position "y," shown in Fig. 9. As the drill fixture 100 proceeds in its movement, the spindle 239 in the block 227 will be moved outwardly and will engage the pointed end of the drill in the manner described hereinbefore. Continued movement of the drill fixture 100 moves the block 227 along the curved upper surface of the straight portion 220 of the track 219 and the drill point will be properly positioned for grinding during such movement. The drill 104 will be properly positioned for grinding, with the lips of the drill in a vertical plane, at the point in the travel of the block 227 along the straight portion 220 of the track 219 at which the cam follower 261 drops off of the exit end of the tapered cam 262. As the drill fixture 100 continues to move, the arm 258 on the block 227 will be disengaged from the drill fixture 100 and such movement of the block 227 will have moved the locator arms 221 so as to move the succeeding block 227 to the point marked "y" in Fig. 9, whereby said succeeding block 227 will be picked up and carried through a locating or indexing operation by the next drill fixture 100. As the drill fixture 100 continues in its movement, the air push button 140 will ride off of the rail 141 and air under pressure will flow through the conduit 137 to force the piston 134 downwardly and the arm 128 will be pivoted to bring the rounded nose 130 of the cam locking means upwardly against the washer 124 to the dotted position shown in Fig. 4, and the drill 104 will be securely locked in position for the grinding operation.

The rotary fixture 89 continues its rotation and brings the drill 104 adjacent the right grinding wheel 265 at a point in the rotary motion of the cam 79 when it is ready to permit movement of the slide 30 outwardly on the slide 12 or transversely away from the grinding wheels 265 and 266 under the action of spring 38 toward the bracket 83 as viewed in Fig. 1. As viewed in Fig. 22, the one side or relief surface 267 of the drill point is then ground from the heel 268 of the relief surface 267 to the lip 269 of said surface, as the rotary fixture 89 is transversely backed away from the grinding wheels 265 and 266.

The heel 268 of the relief surface 267 on the drill point engages the counter-clockwise rotating grinding wheel 265 at the point marked 291, as shown in Fig. 26. The drill 104 is then moved backwardly, longitudinally and circumferentially relative to the wheel 265 and grinding on the relief surface 267 takes place until the tangential point 292 is reached, at which point the lip 269 is ground and the rotary fixture 89 carries the drill 104 away from the wheel 265 and on to the wheel 266. Continued rotation of the rotary fixture 89 brings the other side or relief surface 270 of the drill point into grinding engagement with the wheel 266 at the tangential point 293 on the wheel 266. The lip 271 of the relief surface 270 engages the wheel 266 at the tangential point 293 and as the rotary fixture 89 moves toward the grinding wheel 266, the relief surface 270 is ground from the lip 271 to the heel 272. The grinding action is complete when the heel 272 breaks engagement with the wheel 266 at the point 294. The drill point follows a helical path across the upper diameter of the grinding wheels 265 and 266 during the grinding action, as shown in Figs. 26 and 27.

The foregoing grinding action is illustrative of the

grinding action on one drill. However, during one complete rotation of the rotary fixture 89, fifteen drills will be ground, since the fixture 89 is provided with fifteen stations or drill holding fixtures 100. During one complete revolution of the rotary fixture 89, the cam 79 makes fifteen complete revolutions. The rotary fixture 89 may be provided with more or less stations than shown, but the total number of stations must always be an odd number so that when the fixture 89 is rotatably moving one drill down and away from the grinding wheel 265 after grinding a relief surface 267 it is ready to next move a drill on a fixture 89 upwardly into engagement with the wheel 266 on the forward stroke of the rotary fixture 89 toward the grinding wheels, that is, toward the arm 36, due to the action of cam 79 to grind a relief surface 270. The relief surfaces 267 and 270 are not ground simultaneously but alternately since the total number of fixtures is always an odd number.

After the drill 104 leaves the grinding wheel 266, the rotary fixture 89 rotatably moves the drill fixture 100 in the clockwise direction as viewed in Fig. 3 and the air button 140 will be engaged by the rail 141 as described hereinbefore. The clamp stud 119 will engage the riser bar 169 as described hereinbefore and the clamp plate 106 will unclamp the drill 104 as previously explained. The V-block 103 engages the arm 179 on the ejection means 172 and the ejection means then operates as described hereinbefore to discharge the drill 104 into the chute 197 or any other suitable receiving receptacle. The drill fixture 100 is then carried again to the hopper 158 for re-loading and the cycle is repeated.

The particular machine described would preferably use grinding wheels which are 18" long and 18" in diameter and the rotary fixture 89 would have a 24 inch swing, that is, the diameter of the rotary path of the drills 104 would be approximately 48 inches. The rotary locator track 219 would have a diameter of approximately 14 inches so that the blocks 227 would be picked up by the drill fixtures 100 evenly and smoothly in gearlike action. The particular machine shown is suitable to grind drills up to one-half inch in diameter. The eccentric movement of the cam 79 for the machine shown would be about 2 inches. That is, the distance 88 through which the rotary fixture 89 is moved by the cam 79 causes the drills 104 to be moved longitudinally forwardly and backwardly relative to the grinding wheels 265 and 266 about 2 inches. The aforementioned figures would, however, vary depending on the size or diameter of the drill to be ground. Also, for different desired angles on the drill points, the settings of the grinding wheels 265 and 266 would have to be adjusted accordingly, relative to the rotary fixture 89 and the slides 12 and 30.

If the drill 104 is required to have a different clearance angle, the machine could be provided with grinding wheels mounted to be adjustable in various planes, as shown by the grinding wheels in Figs. 24 and 25. Numeral 295 indicates a grinding wheel mounted on the shaft 296 by means of the end plate 297 and the nut 298. The shaft 296 is suitably rotatably mounted in the end wall 299 of the slide 300. A motor 301 is fixedly mounted on top of the slide 300 and drives the pulley 302 which drives the belts 303 and the pulley 304 which is mounted on the outer end of the shaft 296. The slide 300 is slidably mounted on the dovetail guide 305 on the slide 306, and the screw rod 307 is adapted to move the slide 300 on the guide 305 on the slide 306. The inner end of the rod 307 is threadably mounted in the slide 306 in the usual manner and the other end is rotatably mounted in the block 308 which depends from the slide 300. The outer end of the screw rod 307 is connected by the coupling 309 to the gear reducer 310 which is fixedly mounted on the bracket 311 which is fixed on the block 308 on the slide 300. The gear reducer 310 is connected to a constant speed motor 312 by means of the coupling 313. The motor

312 may thus provide a continuous feeding motion to the grinding wheel 295 and this motor may be reversed by means similar to that used on motor 19 of Fig. 2. The slide 306 is pivotally mounted on the pin 314 which is fixed in the slide 315 and the slide 306 is retained in an adjusted position on the pin 314 by the set screw 316. The slide 315 is slidably mounted on the guide 317 on the block 318. The slide 315 is movable on the block 318 by means of the usual screw rod 319 which is rotatably mounted in the arm 320 which is fixed on the block 318. The screw rod 319 is actuated by means of the handwheel 321. The block 318 is pivotally mounted on the pin 322 which is fixed in the base 323 and the block 318 is retained in an adjusted position by the set screw 324. It will be seen that the modified grinding wheel mounting structure of Figs. 24 and 25 provides a means for adjusting the position of the grinding wheels relative to the rotary fixture 89 for various drill angles.

The invention is described for use in grinding right hand drills but left hand drills may be ground by reversing the action of cam 79 and grinding the drills on the lower diameter of the wheel. It will be understood that the path travelled across the grinding wheels by a drill point will be longer for increasingly larger sized drills, and vice versa. The rotary fixture base 10 and the grinding wheel bases 280 are preferably mounted on a common base plate 325.

While it will be apparent that the preferred embodiments of the invention herein disclosed are well calculated to fulfill the objects above stated, it will be appreciated that the invention is susceptible to modification, variation and change without departing from the proper scope or fair meaning of the subjoined claims.

What I claim is:

1. A machine for grinding points on drills comprising: a base having a longitudinal axis; a rotary drill carrying fixture movably mounted on said base and rotatable in a vertical plane about a horizontal axis disposed at an acute angle to the longitudinal axis of said base; means for moving said fixture on said base in a direction transversely to the longitudinal axis of said base; means for rotating said fixture; releasable clamping means on said fixture for releasably holding a plurality of drills; a pair of laterally spaced apart rotatable grinding wheels, each having a longitudinal axis and being disposed with their longitudinal axes horizontal and parallel to the longitudinal axis of said base; said grinding wheels being disposed adjacent the path of travel of the drill holding means on said fixture; and, means for moving said fixture forwardly and backwardly on said base in a direction parallel to the longitudinal axis of said base and the longitudinal axes of said grinding wheels and in timed relation to the rotation of said fixture, whereby, each of the drills carried by said fixture will be moved into grinding engagement with the periphery of one of said grinding wheels during the backward movement of said fixture for grinding one side of the point on each of the drills, and, the drills will then be moved into grinding engagement with the periphery of the other of said grinding wheels during the forward movement of said fixture for grinding the other side of the point on each of the drills.

2. A machine for grinding points on drills comprising: a base having a longitudinal axis; a rotary drill carrying fixture movably mounted on said base and rotatable in a vertical plane about a horizontal axis disposed at an acute angle to the longitudinal axis of said base; means for moving said fixture on said base in a direction transversely to the longitudinal axis of said base; means for rotating said fixture; releasable clamping means on said fixture for releasably holding a plurality of drills; means for automatically operating said releasable clamping means; a pair of laterally spaced apart rotatable grinding wheels, each having a longitudinal axis, and being dis-

posed with their longitudinal axes horizontal and parallel to the longitudinal axis of said base; said grinding wheels being disposed adjacent the path of travel of the drill holding means on said fixture; and, means for moving said fixture forwardly and backwardly on said base in a direction parallel to the longitudinal axis of said base and the longitudinal axes of said grinding wheels and in timed relation to the rotation of said fixture, whereby, each of the drills carried by said fixture will be moved into grinding engagement with the periphery of one of said grinding wheels during the backward movement of said fixture for grinding one side of the point on each of the drills, and, the drills will then be moved into grinding engagement with the periphery of the other of said grinding wheels during the forward movement of said fixture for grinding the other side of the point on each of the drills.

3. A machine for grinding points on drills comprising: a base having a longitudinal axis; a rotary drill carrying fixture movably mounted on said base and rotatable in a vertical plane about a horizontal axis disposed at an acute angle to the longitudinal axis of said base; means for moving said fixture on said base in a direction transversely to the longitudinal axis of said base; means for rotating said fixture; releasable clamping means on said fixture for releasably holding a plurality of drills; means for automatically operating said releasable clamping means; a pair of laterally spaced apart rotatable grinding wheels, each having a longitudinal axis, and being disposed with their longitudinal axes horizontal and parallel to the longitudinal axis of said base; said grinding wheels being disposed adjacent the path of travel of the drill holding means on said fixture; means for moving said fixture forwardly and backwardly on said base in a direction parallel to the longitudinal axis of said base and the longitudinal axes of said grinding wheels and in timed relation to the rotation of said fixture, whereby, each of the drills carried by said fixture will be moved into grinding engagement with the periphery of one of said grinding wheels during the backward movement of said fixture for grinding one side of the point on each of the drills, and, the drills will then be moved into grinding engagement with the periphery of the other of said grinding wheels during the forward movement of said fixture for grinding the other side of the point on each of the drills; and a drill ejector means for removing the drills from said clamping means after the points have been ground on the drills.

4. A machine for grinding points on drills comprising: a base having a longitudinal axis; a rotary drill carrying fixture movably mounted on said base and rotatable in a vertical plane about a horizontal axis disposed at an acute angle to the longitudinal axis of said base; means for moving said fixture on said base in a direction transversely to the longitudinal axis of said base; means for rotating said fixture; releasable clamping means on said fixture for releasably holding a plurality of drills; means for automatically operating said releasable clamping means; a pair of laterally spaced apart rotatable grinding wheels, each having a longitudinal axis, and being disposed with their longitudinal axes horizontal and parallel to the longitudinal axis of said base; said grinding wheels being disposed adjacent the path of travel of the drill holding means on said fixture; means for moving said fixture forwardly and backwardly on said base in a direction parallel to the longitudinal axis of said base and the longitudinal axes of said grinding wheels and in timed relation to the rotation of said fixture, whereby, each of the drills carried by said fixture will be moved into grinding engagement with the periphery of one of said grinding wheels during the backward movement of said fixture for grinding one side of the point on each of the drills, and, the drills

will then be moved into grinding engagement with the periphery of the other of said grinding wheels during the forward movement of said fixture for grinding the other side of the point on each of the drills; a drill ejector means for removing the drills from said clamping means after the points have been ground on the drills; and, means for automatically loading drills into the drill clamping means after the finish ground drills have been ejected therefrom.

5. The grinding machine as set forth in claim 4, wherein: said machine includes a means for positioning the drills lengthwise in the clamping means.

6. The grinding machine as set forth in claim 5, wherein: said machine includes a drill locator means operable by said rotary drill carrying fixture for locating the drills in said clamping means with the lips of the drills positioned to permit one of said grinding wheels to grind one of the faces on a drill point and the other of said grinding wheels to grind the oppositely disposed other face on a drill point.

7. The grinding machine as set forth in claim 6, wherein: said machine is provided with means for moving said rotary drill carrying fixture longitudinally of said grinding wheels.

8. A machine for grinding points on drills comprising: a base plate; a base having a longitudinal axis fixedly mounted on said base plate; a longitudinally disposed guide on said base; a slide movably mounted on said guide on said base; means for automatically moving said slide on said guide on said base; a guide on said first named slide disposed at a right angle to the guide on said base; a second slide movably mounted on said last named guide; means for moving said second slide backwardly and forwardly on said last named guide; a housing adjustably mounted on said second slide; a rotary drill carrying fixture rotatably mounted on said housing and rotatable in a vertical plane about a horizontal axis disposed at an acute angle to the longitudinal axis of said base; means for rotating said rotary fixture; releasable clamping means on said rotary fixture for releasably holding a plurality of drills; a pair of laterally spaced apart rotatable grinding wheels each having a longitudinal axis, and being disposed on said base plate with their longitudinal axes horizontal and parallel to the longitudinal axis of the longitudinally disposed guide on said base; said grinding wheels being disposed adjacent the path of travel of the drill holding means on said rotary fixture; and, means for automatically operating said releasable clamping means.

9. The grinding machine as set forth in claim 8, wherein: said machine is provided with a drill ejector means for automatically removing the drills from said clamping means as the rotary fixture is rotated and after the points have been ground on the drills.

10. The grinding machine as set forth in claim 9, wherein: said machine is provided with means for automatically loading drills into the drill clamping means after the finish ground drills have been ejected therefrom and as the rotary fixture is rotated.

11. The grinding machine as set forth in claim 10, wherein: said machine is provided with a means for positioning the drills lengthwise in the clamping means as the rotary fixture is rotated.

12. The grinding machine as set forth in claim 11, wherein: said machine is provided with drill locator means operable by said rotary drill carrying fixture for locating the drills in the clamping means in a predetermined rotary position for grinding a first face on a drill point on one of the grinding wheels and a diametrically disposed second face on a drill point on the other one of the grinding wheels as the rotary fixture is rotated.

13. The grinding machine as set forth in claim 12, wherein: said machine is provided with means for adjustably mounting the grinding wheels to permit the grinding of various angles on the point of a drill.

14. The grinding machine as set forth in claim 12, wherein: said means for moving said second slide includes a spring means for moving the second slide backwardly on the last named guide and a cam means for moving the second slide forwardly on the last named guide.
